COMBINATION SUPPORT AND CLOSURE
FLAP FOR LAUNDRY BAGS

Richard J. Pritchard, Manchester, Conn.

Application September 10, 1947, Serial No. 773,105

1 Claim. (Cl. 150—7)

1

This invention relates to bags or flexible receptacles.

An object of this invention is to provide a bag which is designed for carrying soiled linen or the like and which is so constructed and arranged that it can be supported in open position from the back of a chair so that it can be conveniently filled, and when it is either completely or partially filled, the supporting band which half encircles the open end of the bag can be reversed and will then form a closure band which will firmly close the mouth of the bag so that it may be carried from the opposite end.

Another object of this invention is to provide a bag of this kind which includes a pair of pull tabs or loops within the upper portion of the supporting band which will facilitate the reversal of the band from a supporting position to a closure forming position.

To the foregoing objects, and others which may hereinafter more fully appear, the invention consists of the novel construction, combination and arrangement of parts, as will be more specifically referred to and illustrated in the accompanying drawings, but it is to be understood that changes, variations, and modifications may be resorted to which fall within the scope of the invention as claimed.

In the drawings:

Figure 1 is a perspective view from the front of a bag constructed according to an embodiment of this invention.

Figure 2 is a detailed front elevation of the bag when in closed position.

Figure 3 is a perspective view showing the manner of reversing the combined supporting band and closure from a supporting to a closing position.

Figure 4 is a sectional view taken on the line 4—4 of Figure 1.

Figure 5 is a fragmentary sectional view taken on the line 5—5 of Figure 2.

Figure 6 is a fragmentary sectional view taken on the line 6—6 of Figure 2.

Figure 7 is a fragmentary vertical section of one of the upper corners of the bag, showing the reversing loop or tape.

Referring to the drawings, the numerals 10 and 11 designate the front and rear walls of a fabric or flexible bag which are secured together at their lower ends by stitching 12. The upper end of the bag is open and is adapted to be selectively closed as will be hereinafter described. The walls 10 and 11 are secured together at

their opposite lengthwise edges by stitching 13 and 14. The upper end of the front wall 10 is formed with a hem 15 and the upper end of the rear wall 11 is formed with a hem 16 which is disposed on the inner side of the rear wall 11 as shown in Figure 4.

A combined supporting and closure forming band 17 is secured at the opposite vertical edges thereof to the opposite lengthwise edges of the rear wall 11 and is also secured as by stitching 18 along the upper horizontal edge thereof to the upper portion of the rear wall 11 adjacent the lower edge of the hem 16. The lower edge of the combined supporting band and closure forming member 17 is also formed with a reverted hem 19. A pair of looped tapes 20 are secured between the band 17 and the rear wall 11, and when the band 17 is in bag supporting position as shown in Figure 4 the loops or tapes 20 will be disposed in dependent relation as shown in Figure 7.

When it is desired to close the open upper end of the bag, the hands are extended between the band 17 and the rear wall 11, grasping the two loops 20 and pulling these loops downwardly. This downward pulling of the loops 20 will effect a reversing of the band 17 from the rear side 11 to the front side or wall 10 as shown in Figure 5. In the closure forming position of the band 17 the hems 15 and 16 will be disposed in downwardly extending position and will form a reinforcing means for the closed mouth or end of the bag.

The front wall 10 has secured to the lower end thereof a carrying strap 21 so that when the band 17 is in closure forming position the bag may be carried from the bottom of the bag by means of the strap 21.

With a bag as hereinbefore described, the usual draw strings may be eliminated so that it will not be necessary to provide either eyes or tubular hems for the draw strings in order to close the upper end of the bag.

Having thus described my invention, what I claim is:

A bag comprising substantially coextensive front and rear walls secured together along the bottom and opposite side edges thereof, the top edges of said front and rear walls being downwardly reverted to provide upper hems thereon, a combined supporting and closure band having the upper edge thereof fixed to the rear face of said rear wall along the bottom of the upper hem thereof, the opposite side edges of said band being secured to the opposite side edges of said

rear wall, and a pair of depending looped straps having the ends thereof fixed between said upper edge of said band at the opposite ends thereof and said rear wall with the loop portions of said straps depending adjacent said band and outside said bag, said straps providing a means for facilitating the reversal of the position of said band from a supporting position at the rear of said rear wall with said upper hems upstanding to a closure forming position forwardly of said front wall with said upper hems bent inwardly between said front and rear walls to stiffen the upper edges thereof.

RICHARD J. PRITCHARD.
